CHARLES F. MILLER, OF PITTSBURGH, PENNSYLVANIA, ASSIGNOR TO WESTINGHOUSE ELECTRIC & MANUFACTURING COMPANY, A CORPORATION OF PENNSYLVANIA.

UNDERFEED STOKER AND DRAFT-CONTROLLING MECHANISM THEREOF.

1,352,466.

Specification of Letters Patent. Patented Sept. 14, 1920.

Application filed September 19, 1916. Serial No. 120,979.

To all whom it may concern:

Be it known that I, CHARLES F. MILLER, a citizen of the United States, and a resident of Pittsburgh, in the county of Allegheny and State of Pennsylvania, have made a new and useful Invention in Underfeed Stokers and Draft-Controlling Mechanism Thereof, of which the following is a specification.

This invention relates to stokers, particularly to underfeed stokers in which the fuel is fed to the furnace at a point beneath the surface of the fuel bed.

An object of this invention is to produce an improved stoker of the type described, in which new and improved means are employed for regulating draft to the furnace and at the same time for subjecting the grate bars to the cooling influence of the incoming air.

20 A further object is to produce an improved stoker of the type described, in which improved means are employed for mounting both the moving and stationary grate bars, so that the fuel feeding retorts or troughs 25 may be removed without removing the grate bars or the fuel supporting members, or interfering with their adjustment.

20 A further object is to produce a grate bar in which improved means are employed for 30 cooling the fuel supporting surfaces of the bar and at the same time for delivering regulable amounts of air under pressure to different parts of the fuel bed.

35 A further object is to produce a fuel supporting element or a grate bar, in which means are employed for receiving air under pressure at two different points, and for delivering all of the air so received to the fuel bed.

40 These and other objects which will be made apparent throughout the further description of this invention, are attained by means of apparatus embodying the features herein described, and illustrated in the 45 drawings accompanying and forming a part hereof.

In the drawings Figure 1 is a transverse, vertical, sectional view of a stoker embodying my invention, one-half being shown in 50 section along the line A—A of Fig. 3, and the other, in section along the line B—B of the same figure. Fig. 2 is a fragmental perspective view illustrating the arrangement of air boxes employed in the stoker embody-

ing my invention and also illustrating the 55 method of mounting and of actuating the grate bars or fuel supporting elements.

Fig. 3 is a fragmental perspective view of one air box. It is well known to employ a horizontal fuel retort or trough, which extends from the front to the rear of the furnace, and into which fuel is forced by means of plungers or a revolving screw. It is also well known to employ such a retort in connection with either inclined or horizontal 60 fuel supporting members, such as grate bars, which are located on both sides of the retort and on to which fuel is fed from the retort by a crowding or upheaving action 65 of the fuel, occasioned by the introduction of fresh fuel into the retort at a point below the surface of the fuel, contained therein, or of the fuel, located on the fuel supporting members of the furnace. It is also old to employ moving and stationary grate bars, in 70 connection with such a retort, which coöperate to agitate or break up the fuel bed and to gradually move the fuel from the retort toward the outer end of the grate bars, or toward the sides of the furnace. It is 75 also old to supply air under pressure to such furnaces and to cause the air or blast to traverse air passages formed within the grate bars or fuel supporting elements, but, so far as I know, it is new to deliver all or 80 substantially all of the air entering the furnace through the grate bars of a horizontal underfeed stoker and at the same time to 85 separately regulate the delivery of air to different portions of the fuel bed. To the best 90 of my knowledge, it is also new in horizontal underfeed stokers to deliver air or blast under pressure to the grate bars in two streams, and to so construct the air or blast delivery 95 passages of each grate bar that each stream of air or blast will be delivered to a different part of the fuel bed. These novel features form details or part of my present invention.

The stoker illustrated, as an embodiment 100 of my present invention, includes a horizontal or substantially horizontal fuel feeding retort 3, to which fuel is fed, preferably by means of a plunger, from a hopper receptacle located at the front and on the outside 105 of the furnace.

The furnace also includes grate bars which are arranged in two sets, one set being

located on one side and the other set on the other side of the retort 3. The grate bars of each set are mounted on two air boxes which extend substantially parallel to the retort and which supply air to passages formed within the grate bars.

As illustrated the retort 3 extends from the front to the rear of the furnace and is mounted on frames or pedestals 4, which are located at right angles to the longitudinal axis of the retort and extend substantially across the furnace from one side to the other. The grate bars or fuel supporting elements 5 are arranged in two sets, a set being located on each side of the retort. The grate bars of each set are supported by two air boxes 6 and 7, which are mounted on the pedestals 4. It will of course be understood that two or more pedestals are employed and that they are so spaced along the retort as to provide a rigid support for the retort, the grate bars and all the operating parts of the stoker.

As illustrated each pedestal 4 is provided with a recess, located midway between its ends and in which the retort 3 is mounted. As shown the retort consists of side walls 8 and a base plate 9. The side walls extend vertically, with their lower ends engaging longitudinally extending ribs 10, formed on the pedestal, and they are bolted or otherwise secured to the pedestal. The base plate 9 rests on the rib engaging flanges of the side walls 8 and is rigidly secured to the pedestals by suitable means, not shown.

The air boxes 6 are located on opposite sides of the retort 3 and are mounted on the pedestal 4 in such positions that each supports the upper or inner ends of the grate bars of one set. Each air box 6 is substantially rectangular in cross-section and is provided with a longitudinal extending air duct which communicates with blast delivery ports 12 formed in the bar supporting surface of the box.

The air boxes 7 are located near the side walls of the furnace and each is so mounted on the pedestals 4 that it forms a support for the lower or outer ends of the grate bars of one set. Each air box 7 is substantially channel shaped in cross-section and is adapted to deliver air to the grate bars, supported by it, through blast delivery ports 14 formed in its bar supporting surface.

The pedestals 4 not only support the operating parts of the stoker but also form spacers for the blast or air delivery passages of the stoker. The space below the retort and fuel supporting elements of the stoker is divided into three compartments or into chambers 15, 16, and 16' by partition plates 17 which are mounted on the pedestals. The chamber 15 may be termed the primary air chamber and, extending from the front to the rear of the stoker, is adapted to deliver

air under pressure to the air boxes 6 and 7. This chamber communicates with a blast delivery passage 18, which is shown located immediately below the retort 3, consequently the air delivered through the passage 18 is divided into two streams which pass to opposite sides of the furnace.

Air is delivered from the chamber 15 to the air boxes 6 through passages or ports 19 provided in supporting lugs 20 which are formed on the pedestal. Each supporting lug forms a journal or bearing for a rock shaft 21 and also supports one air box 6. As illustrated each air box 6 is provided with a depending extension 22, in which a port 23 is formed for delivering air from one of the passages 19 to the interior passage of the box. Each box 6 is also provided with longitudinally extending ribs 24 which are spaced to correspond to the space of the pedestal 4 and which are consequently located immediately above the inlet ports 23 with which the box is provided. These ribs engage the upper face of supporting lugs 20 of different pedestals and each box is adapted to be clamped to the outer lateral face of its supporting lug by means of bolts or other suitable means so as to place the ports 23 of the box in direct communication with the passages 19 of the pedestals.

The air boxes 7 are mounted on the pedestals 4 in such a way that their flanges extend downwardly and subtend upwardly projecting mounted lugs 25 formed on the pedestal. With this arrangement the open side of the channel section of each box 7 is in free communication with the chamber 15.

The grate bars 5 are substantially similar in external contour but every other bar of each set is adapted to reciprocate or to move longitudinally toward and away from the retort. For this reason every other bar is provided with downwardly projecting prongs 26 which engage the rock shaft 21 and through which the reciprocatory motion, imparted by the rock shaft, is transmitted to the bars. The stationary bars are provided with downwardly extending lugs 27 which engage opposite sides of the air box 6 and hold the bars in place.

The air blast, delivered to the fuel bed, is first passed through the grate bars for the purpose of cooling the grate bars and at the same time preheating the air. Inasmuch as each grate bar receives blast from two sources, namely, an air box 6 and an air box 7, it is provided with two air passages which, as illustrated, deliver air to different parts of the fuel bed. Each port 12 of the air boxes 6 communicates with air passage 28, formed in the retort end of one grate bar. Each grate bar is therefore provided with an admission port, which communicates with the passage 28 and which is formed in that portion of the bar which engages the bar 130

supporting surface of its supporting box 6. Each grate bar is also provided with twyers 29, which are located in the inner end face of the bar and which are adapted to deliver 5 air from the passage 28 to the fuel as it issues from the retort 3. Each grate bar 5 is also provided with an air passage 30, which communicates with one of the ports 14 of one of the air boxes 7 and delivers air to 10 one or the other of the secondary air chambers 16 or 16', after the air has passed through the greater portion of the bar. This is accomplished by providing an air delivery port 31, in each bar, which is located near 15 the partition, separating the passages 30 and 28, and is adapted to discharge the air from the passage 30 downwardly into one of the secondary air chambers. The inlet port to the passage 30 of each grate bar is formed 20 in the face of the bar which engages the air box 7. The air delivery passages of the stationary and moving grate bars are similar. The ports 12 and 14 are so proportioned, with relation to the registering ports of the 25 grate bars, that the flow of air into the moving bars is not throttled by the reciprocation of the bars nor are the air ports in either the bars or the air boxes uncovered at any time during the motion of the bars. 30 The blast issuing from the ports 31 of the grate bars and entering the secondary air chambers passes upwardly between the grate bars and is delivered to that portion of the fuel bed supported by them. For this reason 35 the bars are provided with spacing pads 33 which are located on each side of each bar and at each end thereof.

During the operation of the stoker fuel issuing from the retort is distributed over 40 both sets of grate bars and the fuel bed assumes a contour somewhat similar to the dotted line in Fig. 1. The green fuel enters the thickest portion of the fuel bed and consequently it is desirable to be able to control 45 the supply of air to this portion of the fuel bed independently of the air delivered to the thinner portions of the bed, located on the grate bars. This is accomplished by providing a damper 34, in the primary air 50 chamber 15 and between the air delivery passage 18 and each air box 7. As illustrated these dampers extend from the front to the rear of the chamber 15 and may be operated from the front of the furnace to 55 cut down the air supply to the air boxes 7 and consequently to the secondary air chambers and in this way permit the blast to the thicker portion of the fuel bed to be increased without the liability of blowing 60 holes through the thinner portion. The continuous delivery of fuel into the retort causes the fuel to distribute itself over the grate bars 5 and finally to be delivered on to dump grates 35, which are located on each 65 side of the furnace and extend from the

front to the rear thereof. As illustrated the dump grates are pivotally mounted on brackets 36 carried by the air boxes 7 and are located at the outer ends of the grate bars. The reciprocating motion of the moving grate bars aids the distributing of fuel over the fuel supporting elements and also tends to break up the fuel bed and feed the fuel downwardly along the grate bars. The ash and clinkers are discharged into the ash 70 pit by lowering the dump grates 35 and as illustrated each furnace is provided with two ash pits one located at each side thereof. 75

The secondary air chambers 16 and 16' receive all the coal or fuel which may sift 80 through the openings between the grate bars or through the openings between the inner ends of the grate bars and the upper edges of the retort. The pedestals 4 are so formed that each secondary air chamber is provided 85 with two downwardly inclined walls which terminate in a flat floor 37. Inasmuch as the secondary air chambers extend from the front to the rear of the furnace the siftings may be readily removed therefrom by providing a door for each secondary air chamber which may be located in the front of the furnace and may be of substantially the same width as the floor 37. It will also be 90 apparent that this arrangement of the partition plates 17 prevents the coal siftings from interfering with the operation of the stoker, since there is no tendency for it to interfere with the operation of the rock shaft 21 nor is there any possibility of its entering 95 the air chamber 15.

By supporting the grate bars on the air boxes it is possible to remove the retort without in any way interfering with the adjustment of the grate bars and it is also possible 105 to remove the grate bars and their operating mechanism without interfering with the operation of the retort or its fuel feeding means.

The rock shaft 21 may be operated by the 110 usual form of stoker drive mechanism, and it will be apparent, while I have illustrated but one embodiment of my present invention, that various changes, modifications, substitutions, additions and omissions may be 115 made in the apparatus illustrated without departing from the spirit and scope of the invention as set forth by the appended claims.

What I claim is:

1. An underfeed stoker comprising a retort, and grate bars adapted to receive fuel from the retort, each grate bar being provided with twyer openings at its retort end and a delivery passage communicating therewith, and a separate air delivery port and a separate passage communicating therewith, means for dividing the space below the grate bars into a primary and a secondary air chamber and means for delivering air from the primary air chamber to 120

125

130

the separate passages of each grate bar, the said air delivery port being adapted to deliver air to the said secondary chamber.

2. An underfeed stoker comprising a retort, and grate bars adapted to receive fuel from the retort, each grate bar being provided with twyer openings at its retort end and a delivery passage communicating therewith, and a separate air delivery port and a separate passage communicating therewith, means for dividing the space below the grate bars into a primary and a secondary air chamber and means for delivering air from the primary air chamber to the separate passages of each grate bar, said secondary air chamber receiving air through the ports formed in the grate bars, and discharging the air between the grate bars into the fuel thereon.

20 3. An underfeed stoker comprising a fuel feeding retort, grate bars receiving fuel therefrom, an air chamber beneath the bars adapted to discharge air between the bars into the fuel thereon, each of the said bars being provided with a pair of independent air passages, one of which discharges air into the said air chamber and two air boxes for supporting the grate bars, one of which is adapted to deliver air to one passage of each bar and the other of which is adapted to deliver air to the other passage of the bar.

4. An underfeed stoker comprising a fuel feeding retort, grate bars receiving fuel therefrom, an air chamber beneath the bars adapted to discharge air between the bars into the fuel thereon, each of the said bars being provided with a pair of independent air passages, one of which discharges air into the said air chamber, a pair of air boxes for supporting the grate bars, one of which is adapted to deliver air to one passage of each bar and the other of which is adapted to deliver air to the other passage of the bar, and means for controlling the delivery of air through one of the said boxes.

5. An underfeed stoker comprising a retort, grate bars adapted to receive fuel from the retort and supporting means for the retort and grate bars, each grate bar being provided at its retort end with twyer openings, an air passage for delivering air thereto, and an inlet port communicating with the passage, each grate bar being provided with a second inlet port located near the other end thereof, a passage communicating with the second port and extending throughout the greater portion of the bar and a delivery port located in the lower face of the bar and communicating with the last mentioned passage.

6. A grate bar having twyer openings formed in one end thereof, a passage formed therein and communicating with the opening and having an inlet port communicating therewith, a second passage formed in

the grate bar, a delivery port located in the lower face of the bar, and intermediate its ends, and communicating with the second passage, and an inlet port located in the opposite end of the bar from the twyer openings and communicating with the second passage.

7. In an underfeed stoker, a fuel feeding retort, an ash discharge mechanism, a set of grate bars located between the retort and said mechanism, two air boxes, one located adjacent the ash discharge mechanism and one adjacent the retort ends of the bars for supporting the bars and for delivering air under pressure to separate passages formed within the bars, a primary air delivery chamber located beneath the grate bars and communicating with each air box, a secondary air delivery chamber located immediately below the grate bars and receiving air from the primary chamber through passages of the grate bars.

8. An underfeed stoker comprising a fuel feeding retort, a dump grate mechanism, a set of grate bars located in parallel relation and extending from the retort to said mechanism, each grate bar being provided with two separate air delivery passages, one having an inlet at one end of the bar and an outlet adjacent the opposite end of the bar adapted to discharge air beneath the bar, and the other an inlet intermediate the ends of the bar and outlet ports discharging into the fuel upon the bar, and two air boxes for supporting the grate bars and each delivering air to a separate set of air passages of the bars.

9. An underfeed stoker comprising a fuel feeding retort, a dump grate mechanism, a set of grate bars extending in parallel relation and located between the retort and said mechanism, each grate bar being provided with two separate passages, one having an inlet located intermediate the ends of the bar, and communicating with twyers formed in the retort end of the bar, and the other having an inlet formed in the ash discharge end of the bar and communicating with a delivery port formed in the lower face of the bar adjacent to the inlet to the first mentioned passage, two air boxes for supporting said grate bars, each delivering air under pressure to one of the inlets of every bar, pedestals on which said retort and air boxes are mounted, and partition plates mounted on the pedestal and dividing the space below the bars into a primary air chamber communicating directly with both air boxes, and a secondary air chamber located immediately below the grate bars and receiving air from the air delivery ports located in the bottom of the grate bars.

10. An underfeed stoker comprising a centrally located retort, an ash discharge mechanism located on each side of the re-

70

- tort and extending parallel therewith, a separate set of grate bars located on each side of said retort and each extending from the retort toward an ash discharge mechanism, each grate bar being provided with two separate air passages, one having an inlet formed near the ash discharge end of the bar and an air delivery port formed in the lower face of the bar intermediate the ends thereof, the other passage having an inlet formed near the retort end of the bar and communicating with twyer openings located in the retort end of the bar, two air boxes for supporting each set of grate bars, each delivering air to one inlet of each bar of one set, a pedestal on which said retort and all said air boxes are mounted, and partition plates mounted on the pedestal and dividing the space below the furnace into a primary air chamber, which communicates with all the air boxes, and two secondary chambers, each being located immediately below one set of grate bars and receiving air from the air delivery ports of the bars under which it is located.
11. An underfeed stoker comprising a central retort, two ash discharge mechanisms, one located on each side of the retort and extending substantially parallel therewith, a separate set of grate bars between the retort and each of said mechanisms, each grate bar having two separate air passages formed therein, one having an inlet at the ash discharge end of the bar and communicating with an air delivery port located in the bottom of the bar intermediate the ends thereof, the other having an inlet located intermediate the ends of the bar and communicating with twyer openings located in the retort end of the bar, two air boxes on which each set of grate bars is mounted, each communicating with one inlet of each bar supported thereon, a pedestal on which all the air boxes are mounted, partition plates mounted on the pedestal and dividing the space below the air box into a primary air chamber which communicates with all the air boxes, and two secondary air chambers, each of which communicates with the air delivery ports of the bars under which it is located, and means for separately controlling the delivery of air to each secondary air chamber.
12. In combination in an underfeed stoker, a retort, a pedestal supporting the retort and having an upwardly projecting lug formed thereon provided with an air delivery passage, partition plates mounted on the pedestal forming an air chamber communicating with the said passage, an air box mounted on said lug and having an inlet registered with the said passage, and grate bars supported on said air box provided with air passages adapted to receive air from the said box.
13. An underfeed stoker comprising a fuel feeding retort, grate bars receiving fuel therefrom, an air chamber beneath the bars adapted to discharge air between the bars into the fuel thereon, each bar being provided with a pair of independent air passages, one of which is adapted to discharge air into the said chamber and the other of which is adapted to discharge air into the fuel upon the bar, and a separate air box communicating with each passage of the grate bar and adapted to deliver air to the passage in communication therewith.
14. An underfeed stoker comprising a pedestal construction having supporting elements for two groups of grate bars and an intermediate retort, a removable retort carried by said retort supporting elements, and a group of removable grate bars supported by said grate bar supporting elements at each side of the retort.
15. An underfeed stoker comprising a pedestal structure, a central retort, grate bars removably carried by said pedestal structure, wall elements carried by said pedestal structure and, together with the retort, defining a primary air chamber, the wall elements beneath the grate bars defining secondary air chambers, each grate bar having independent passage-ways communicating with the primary air chamber, one discharging continuous to the retort discharge and the other discharging into a secondary air chamber, said secondary air chambers being covered by the grate bars whereby the preheated air therein may escape between bars to support combustion.

In testimony whereof I have hereunto subscribed my name this 18th day of September, 1916.

CHARLES F. MILLER.
